SOCK DRYING DEVICE

Albert J. Leonard, Sr., Glendale, Calif.

Application June 19, 1950, Serial No. 169,002

2 Claims. (Cl. 223—77)

1

My invention relates generally to wearing apparel, and more particularly to supports or forms to which socks or stockings may be applied for the purpose of drying such articles after being washed.

An object of my invention is to provide a sock drying device which is structurally characterized by a resilient, normally expanded frame whose marginal contour defines foot and ankle portions co-acting to support a wet sock against shrinking while drying, the device embodying simple and conveniently operable means by which the drying frame can be releasably retained in a collapsed position upon movement of the frame thereto, so as to leave both hands of the operator free to apply a wet sock to the frame with the utmost ease and dispatch and without danger of tearing or stretching the sock particularly at the heel portion thereof, all while enabling the frame to be instantly released from the action of the retaining means, so that under its urging tendency the frame will return to its expanded, sock-supporting position.

A further object of my invention is to provide a sock drying device of the above described character which is of extremely simple, one-piece construction capable of being formed by simple bending operations to cheaply produce the completed article, whereby to enable the device to be sold at a comparatively low cost.

With these and other objects in view, my invention resides in the combinations and arrangements of elements as set forth in the following specification and particularly pointed out in the appended claims.

In the accompanying drawings:

Figure 1 is a view in front elevation, of one form of sock drying device embodying my invention;

Figure 2 is a view of the sock drying device in side elevation; and

Figure 3 is a transverse sectional view taken on the line 3—3 of Figure 2.

Referring specifically to the drawings, my invention in its illustrated embodiment is preferably constructed from a single length of non-rusting or suitably coated wire to provide a resilient, skeletal frame F the plan of which has the contour of a sock of a predetermined size, when laid flat, all to define a foot portion 10 and an ankle portion 11. The foot portion 10 includes front and rear members 12 and 13, respectively, whereas the ankle portion 11 has front and rear members 14 and 15, respectively, extending from the respective members of the foot portion. The

members 14 and 15 are laterally offset towards each other adjacent to their upper ends as indicated at 16 and 17, respectively, to conform to the conventional narrowed top of a sock.

5 The rear members 13 and 15 of the foot and ankle portions, respectively, join to form the heel portion 18, whereas the front and rear members 12 and 13 of the foot portion join to form the toe 19 which provides a spring and fulcrum about which the front members 12 and 14 are urged laterally outward relative to the rear members 13 and 15.

10 From the upper or free end of the rear ankle member 15 projects a connector arm 20 (Figure 3), the free end of which arm is return bent at 21 about the front ankle member 14 and is extended to provide a second arm 22 parallel to the arm 20. The arms 20 and 22 co-act to define a slot 23 in which the front ankle member 14 is freely received. Adjacent to its free end, the arm 22 is indented towards the arm 20 to provide a keeper 24 which is beveled at opposite sides to form cam surfaces 25 and 26 over which the front ankle member 14 is adapted to ride. The free end 15 of the arm 22 is curved towards the arm 20 as indicated at 27 for co-action with the arm 20 and with the keeper 24 in providing an opening 28 in which the front ankle member 14 is adapted to be releasably retained by the keeper 24, so as to maintain the frame F in its contracted or collapsed position as shown in broken lines in Figure 2.

15 The free upper end of the front ankle member 14 extends beyond the connecting arm 19 for a short distance as indicated by 29 to form a hook 30 by which the device is adapted to be suspended from a clothesline or other support.

20 In operation, the front members 12 and 14 as one unit, and the rear members 13 and 15 as another unit, are normally urged away from each other about the toe portion or fulcrum 19 to the extended or expanded position shown in full lines in Figure 2, which position is definitely limited by engagement of the front ankle member with the closed end of the slot 23. It will be noted that the arms 20 and 22 are normally urged towards each other until the keeper 24 and curved end 27 of the arm 22 engage the arm 20 as shown in Figure 3.

25 To apply a wet sock to the frame F, the frame is first contracted by pressing the front and rear ankle members 14 and 15 towards each other until the front ankle member rides over the cam surface 25 and forces the arm 22 away from the arm 20, so as to enable the front ankle member

to pass the keeper 24 and snap into the opening 28 wherein the member is confined by the keeper so as to releasably retain the frame in its contracted position as shown in broken lines in Figure 2.

The wet sock may now easily be applied to the constructed frame by using both hands of the operator which are free for this purpose, and without any resistance being offered by the frame particularly at the heel portion thereof. Danger of tearing or stretching the sock when applying it to the frame is thus eliminated by the automatic retention of the frame in its contracted position.

When the sock is applied to the frame, the front ankle member 14 is pressed by the thumb in a direction away from the rear ankle member 15 so as to cause the front ankle member to ride over the other cam surface 26, thus again forcing the arm 22 away from the arm 20 until the member 14 passes the keeper 24 and is free under its natural urging tendency, to return to its normal position shown in full lines in Figure 2. The sock will now be held taut and will have practically all its surface exposed for the circulation of air to expedite drying of the sock without shrinking, when the device is hung by the hook 30 from a clothesline or other support.

I claim:

1. A drying device of the class described comprising: a skeletal frame having the configuration of a sock when flat, to provide front ankle and foot members, rear ankle and foot members joined by a heel portion, and a resilient, fulcrum-forming toe portion urging the frame to an expanded position; the free end of one of said ankle members projecting laterally towards the other ankle member to provide a connector arm; a second arm resiliently connected at one end to said connector arm and co-acting therewith to define therebetween a slot freely receiving said other ankle member to definitely limit

the expanded position of the frame, yet rendering the latter contractible to freely receive a sock to be dried; and a keeper carried by one of said arms, with which said other ankle member is co-actable to latch the frame in a contracted position so as to leave both hands of the operator free for the application of a wet sock to the frame.

2. A drying device of the class described comprising: a frame composed of a length of resilient wire bent into the configuration of a sock when flat, so as to provide front ankle and foot members, rear ankle and foot members joined by a heel portion, and a resilient, fulcrum-forming toe portion urging the frame to an expanded position; the free end of one of said ankle members being bent laterally towards the other ankle member to provide a connector arm return bent at its free end to form a second arm resiliently connected to the connector arm and co-acting therewith to define a slot receiving said other ankle member to limit the expanded position of the frame; said second arm being indented at its free end portion towards the connector arm to provide a keeper beveled at opposite sides to form cam surfaces over which said other ankle member is adapted to ride to latch the frame in a contracted position for the application of a wet sock to the frame.
